UNITED STATES PATENT OFFICE.

ROSWELL A. LANCEY AND CHARLES W. SMITH, OF TOWNSEND, MASSACHUSETTS, ASSIGNORS TO ANSON D. FESSENDEN, OF TOWNSEND, MASSACHUSETTS.

MECHANISM FOR FINISHING THE ENDS OF BARRELS.

SPECIFICATION forming part of Letters Patent No. 758,670, dated May 3, 1904.

Application filed October 5, 1903. Serial No. 175,729. (No model.)

To all whom it may concern:

Be it known that we, ROSWELL A. LANCEY and CHARLES W. SMITH, of Townsend, county of Middlesex, and State of Massachusetts, have invented certain new and useful Improvements in Mechanism for Finishing the Ends of Barrels, of which the following is a specification.

The objects of our invention are as follows: 10 to provide means for smoothing or finishing the ends of a barrel that will accomplish the work quickly and leave the surfaces smooth and free from indentations due to the slivering of the material and to provide cutter-holding devices that may be easily adjusted and that 15 will cause the cutters to accomplish their work one after another in a predetermined order.

In the drawings illustrating our invention and the best mode now known to us of accomplishing the same, Figure 1 represents a front elevation of a rotary cutter-head with the cutters mounted thereon. Fig. 2 represents a sectional view through line 2 2, Fig. 1. Fig. 3 is a sectional view through line 3 3, Fig. 1. Fig. 4 is a view of the chamfering-cutter and the block to which it is attached. Fig. 5 is a sectional view of the leveling-cutter and the block to which it is attached. Fig. 6 is a view of the howeling-cutter and the supporting-block for same. Fig. 7 is a sectional view of the crozing-cutter and the supporting-block for same. Fig. 8 is an enlarged view of the howeling-cutter, which better illustrates its shape and the method of holding it. Fig. 9 is an enlarged view of the crozing-cutter, showing its shape and the shape of the cutting edge. Fig. 10 is an end view of the crozing-cutter, which better illustrates its shape. Fig. 11 is a sectional view through line 11 11, Fig. 1, 35 showing a section of the revolving cutter-head and the method of securing the two supporting-blocks and slide supporting same.

In the drawings, A illustrates a revolving head. B is a dovetail groove running across the face of the revolving cutter-head, and B' is a similar dovetail groove running across the face of the revolving cutter-head A at substantially right angles to the dovetail groove B.

C is a slide-block dovetailed to fit and slide in the groove B and is of a length sufficient 50 to extend very nearly the whole length of said groove and has on its inner face an inwardly-extending cam portion C', having the diagonal slots C² cut in its inner faces arranged to receive the pins C³, attached to the end of the 55 sliding rod C⁴.

The object of the cam C², pin C³, and the sliding rod C⁴ is as follows: When said sliding rod C⁴ is moved longitudinally or endwise at right angles to the face of the revolving cutter-head A, it will move the slide-block C endwise and cause the cutters mounted thereon to contact with the end of a barrel.

Mounted upon the slide-block C are cutter-supporting blocks D and D', secured thereto 65 by the T-head bolts D² D². The bolts D² D² have T-shaped heads adapted to fit and slide in the T-shaped slot D³ in order that said blocks D and D' may be adjusted longitudinally in or out from the center of the revolving cutter-head A. Adjusting-blocks E and E' are also attached to the slide C by similar bolts and have threaded therein adjusting-screws E² E². The purpose of these adjusting-screws is as follows: When it is desired to 75 sharpen the cutters mounted in the cutter-blocks D and D', the bolts D² D² are loosened and the cutters and cutter-supporting blocks removed, the cutters being sharpened while attached to the blocks. When sharpened, they 80 may be returned to the exact position they occupied before removal, as shown in Fig. 1, or again in contact with the screws E² E², thereby preserving the same position that they occupied before being removed. The screws 85 E² E² also serve the purpose of allowing the operator to get a fine adjustment of the cutters supported by the cutter-blocks D and D'.

F is the leveling-cutter and is adapted to be moved inward from the outside of the 90 barrel, thereby cutting inward, making the outside edge of the end of the barrel after being cut or leveled by said cutter F smooth.

G is the chamfering-cutter, which moves outward to chamfer the inside edge of the 95 barrel. The movements of the cutters F and

G are more clearly shown in Figs. 4 and 5. Short sliding blocks H and I are mounted in and slide in the dovetail groove D'. The inner ends of these sliding blocks are provided with 5 the inclined slots K and L, in which the pins M and M' are free to slide. These pins M and M' are mounted upon a cross-piece M², which in turn is attached to the slide C and is moved thereby. It will be seen that any 10 movement of the slide C in the direction of the arrow will cause the block H to move outward and the slide-block I to move outward and be drawn inward again. The purpose of the double movement of the slide I 15 will be more fully explained hereinafter.

H' is a tool-supporting block adjustably attached to the slide-block H, and H² is an adjusting-block secured to the slide H, having an adjusting-screw H³ threaded therein in 20 such manner as to contact with the inner end of the block H'. The slide I has also adjustably mounted thereon the tool-holding block I' and adjusting-block I², having threaded therein the adjusting-screw I³. There is mounted upon the tool-block H' the howeling-cutter F', and upon the tool-block I' is mounted the crozing-cutter G'. The purpose of the adjusting-block I² and the adjusting-screw I³ is 25 the same as has been stated for the adjusting-block E' and the adjusting-screw E².

The operation of our improved barrel-finishing revolving head and the cutters mounted thereon is as follows: Referring to Fig. 3, when the slide-rod C⁴ is moved inward in the 30 direction of the arrow the pin C³ will slide downwardly in the slot C², thereby moving the slide C in the direction of the arrow, causing the leveling-cutter F to move inward and cut off the end of the barrel and the 35 chamfering-cutter G to move outward toward the inside of the barrel and chamfer the chime thereof, as shown in Fig. 4; but the cutter F is so positioned as to contact with the outside edge of the barrel and commences to 40 cut it before the chamfering-cutter G commences its cut, so that said leveling-cutter F will have completed its cut and have moved beyond the end of the barrel, as shown in Fig. 45, before the chamfering-cutter G has completed its cut, as is shown in Fig. 4. This arrangement and rotation of the operation of cutters F and G produces a smooth end and leaves the inner and outer edges of the end of the chime smooth and free from any indentations or slivers, which is a very essential point in the construction, especially of pine barrels. The cutters F' and G' are arranged to move 50 outward to cut a howeling-groove and a crozing-groove to receive a barrel-head. The 55 shape of the crozing-cutter G' is more particularly shown in Figs. 9 and 10, which shape enables the operator to cut a very smooth crozing; but the cutter G' is so shaped that it must perform its cut quickly or substantially in two revolutions of the revolving cut-

ter-head; otherwise it would rub against the wood, heat, and draw its temper. For this reason the block I is provided with what might be termed the "double cam-surface" L, in order that the crozing-cutter G' will quickly 70 perform its cut and be withdrawn from the material while the howeling-cutter F' is completing the operation of cutting the howel-groove.

The shape and the rotation in which the 75 cutters illustrated in the drawings perform their operation of finishing the ends of a barrel is the important and essential feature of this invention, for in machines heretofore designed for finishing the ends of barrels wherein 80 the cutters are held rigidly in a revolving cutter-head and moved thereby to contact with the barrel it has been impossible to finish the ends of barrels smoothly, for the reason that the cutters would heat and get dull and tear or 85 remove the material by abrasion. These objections have been fully overcome by the form 90 of cutters and the manner in which they perform the operation of cutting in our device.

This application is designed to supplement 95 our application for a patent filed April 1, 1903, Serial No. 150,592.

Having described our invention and its mode 95 of operation, what we claim is—

1. In a revolving cutter-head for finishing the ends of a barrel, a cutter-supporting head; radial grooves in said cutter-supporting head; a cutter-supporting device slidably mounted in said grooves; a slide-rod mounted to move 100 at right angles to the face of said cutter-supporting head; pins in the inner end of said slide-rod; inclined cam-slots in said cutter-supporting slide; a cross-bar attached to said cutter-supporting slide having pins in its outer 105 ends; a pair of cutter-supporting slides mounted in two of said grooves; cam-slots in their inner ends adapted to receive the pin in the cross-bar; a crozing and a howeling cutter mounted on said slide-blocks and adapted to 110 be moved radially through the movement of said cross-bar as set forth.

2. In a revolving cutter-head for finishing the ends of barrels, radial grooves in the face thereof; a cutter-supporting slide slidably 115 mounted therein and extending substantially across the face of said cutter-supporting head; independent cutter-supporting slides in the other grooves in said cutter-supporting head; means for moving the first-named slide; and means for moving the last two named slides from the first slide as set forth.

3. In a revolving cutter-carrying head for finishing the ends of barrels, radial grooves in the face thereof; a cutter-supporting slide 125 slidably mounted therein and extending substantially across the face of said cutter-supporting head; independent cutter-supporting slides in the other of said grooves; cams for moving said first-named slide; a chamfering 130

and leveling cutter adjustably mounted thereon in such manner that the leveling-cutter will cut from the outside and the chamfering-cutter from the inside of the ends of a barrel, 5 and complete its cut after the leveling-cutter has completed its cut; and means for moving the independent slides from the first slide as set forth.

4. In a revolving cutter-carrying head for fixing the ends of barrels, radial grooves in the face thereof; a cutter-supporting slide slidably mounted therein and extending substantially across the face of said cutter-supporting head; independent cutter-supporting 15 slides in the other of said grooves; cams for moving said first-named slide; a chamfering and leveling cutter adjustably mounted there-

on in such manner that the leveling-cutter will cut from the outside and the chamfering-cutter from the inside of the ends of a barrel, 20 and complete its cut after the leveling-cutter has completed its cut; and means for moving the last two named slides from the first slide in sequence so that the crozing-cutter will complete its cut before the howeling-cutter 25 has completed its cut.

In witness whereof we have hereunto set our hands, in the presence of two subscribing witnesses, this the 30th day of July, A. D. 1903.

ROSWELL A. LANCEY.
CHARLES W. SMITH.
